UNITED STATES PATENT OFFICE.

ALBERT DANZER, OF HAGERSTOWN, MARYLAND, ASSIGNOR TO DANZER METAL WORKS, OF HAGERSTOWN, MARYLAND.

DESIGN FOR A SNOW-GUARD FOR ROOFS.

46,202.

Specification for Design.

Patented Aug. 4, 1914.

Application filed May 27, 1913. Serial No. 770,256. Term of patent 14 years.

To all whom it may concern:

Be it known that I, ALBERT DANZER, a citizen of the United States, residing at Hagerstown, in the county of Washington and State of Maryland, have invented a new, original, and ornamental Design for a Snow-Guard for Roofs, of which the following is a specification, reference being had to the accompanying drawing, forming part thereof.

The figure is a plan view of a snow-guard showing my new design.

I claim:—

The ornamental design for a snow guard for roofs, as shown.

ALBERT DANZER.

Witnesses:

HUGH K. TROXELL,
ROY DANZER.
